UNITED STATES PATENT OFFICE.

HUBERT R. CRANE, OF LOS ANGELES, CALIFORNIA.

FLUSH-VALVE-BULB GUIDE.

Application filed February 19, 1924. Serial No. 693,763.

To all whom it may concern:

Be it known that I, HUBERT R. CRANE, a citizen of the United States, residing at Los Angeles, in the county of Los Angeles and 5 State of California, have invented new and useful Improvements in Flush-Valve-Bulb Guides, of which the following is a specification.

This invention relates to valve guides and 10 it has special application to valves employed in flush tanks.

One object of my invention is the provision of means for properly positioning a valve on its seat.

15 Another object of my invention is the provision of a detachable guide for a valve.

A further object of my invention is the provision of a guide which may readily be attached to and detached from a flush valve 20 bulb.

With the foregoing objects in view, together with such other objects and advantages as may subsequently appear, my invention consists in the construction and arrangement of parts hereinafter described 25 and claimed and illustrated in the accompanying drawings, in which:—

Figure 1 is an elevational view of a flush tank partly in section, showing a discharge pipe in section and a valve to which is attached my improved means for guiding the 30 valve, the valve being shown in closed position.

Fig. 2 is an elevational view of a flush tank partly broken away and partly in section, showing connection to a discharge pipe and a valve raised from its seat.

Fig. 3 is a central longitudinal section of 40 a flush valve bulb and a gude of my invention, and

Fig. 4 is a plan view of Fig. 3.

Referring to the drawings for a more detailed description thereof, the numeral 7 indicates a flush tank having a bottom 8, provided with an aperture 9 thru which passes a threaded nipple 10.

A pipe 14 has an outwardly extending upper flange 15 which abuts against a plate 12 having a central aperture, the plate 12 being held against the lower end of the nipple 10. The pipe 14 is secured to the plate 12 by a coupling 17 which threadedly engages the nipple 10 and which is recessed 50 to support the flange 15 of the pipe 14.

55 Encircling the aperture 9 in the bottom 8 of the tank 7 and resting on the upper face

of the bottom 8 is a valve seat 18 adapted to receive a valve 20. The valve 20, as shown in Fig. 3, is a hollow circular body, the lower periphery of which is outwardly 60 convex. The valve 20 is preferably made of rubber and comprises a boss 21, in the upper portion of which is inset a metallic body 22 having a threaded aperture 22a in axial alignment with the bulb 20 and is 65 adapted to threadedly engage a vertical rod or stem 23, as shown in Figs. 1 and 2.

The bottom portion of the valve bulb 20 is provided with an aperture 25 adapted to receive a valve guide 27 constructed in accordance with my invention. The guide 27 comprises an elongated hollow circular body provided with a longitudinal aperture 28 extending therethru and having the lower portion of its periphery tapered. The guide 70 27 is provided at its upper end with a circular flange 29 which is held against the portion of the inner surface of the valve 20 surrounding the aperture 25, thus furnishing means for detachably securing the guide 75 27 to the valve 20.

In the operation of previous flush tank valves considerable annoyance has been experienced by an improper seating of the valve, resulting from its displacement from 80 the true position.

In the operation of my device, however, during the closing action of the valve the guide 27 will engage the aperture in the transverse plate 12 and pass therethru, thus 85 functioning to properly seat the valve 20.

It will be understood that the guide 27 will not fail to engage the aperture in the transverse plate, since the maximum displacement of the valve 20 which may occur 90 is not sufficient to throw the axis of the guide outside the periphery of the aperture in the plate 12, and it will be seen that when the lower end of the guide 27 is within the aperture in the plate 12 it will be brought 95 to its proper position in the aperture even though its axis may not coincide with the axis of the plate aperture when it first enters the latter. The axial coincidence of the aperture in the plate 12 and the guide 27 will 100 effect a proper seating of the valve 20, inasmuch as the latter is axially aligned with the guide 27 as well as with the seat 18 and the aperture in the plate 12.

It will be seen that according to my invention either the valve 20 or the guide 27 110 may be replaced with a corresponding new

part when worn out and if the flange 29 of the guide 27 is made of rubber it may be pulled or pushed through the aperture in the bottom of the valve 20.

5 While I have herein described one form of my invention, modifications thereof may be devised without departing from the spirit thereof, and it is to be understood that such modifications come within the scope 10 of this invention.

I claim as my invention:

1. A flush valve bulb-guide comprising an elongated tapered rubber member provided with a flange adapting it to be attached to 15 a flush valve bulb.

2. A flush valve bulb guide, comprising an elongated tapered rubber member having a longitudinal aperture therethru and provided with a flange adapting it to be attached to a flush valve bulb.

3. In combination, a hollow flush valve bulb having an aperture thru its bottom and an elongated tapered flanged guide passing thru said aperture and depending from said bulb, being held thereto by the contact of its flange with the inner face of said bulb.

4. In combination, a hollow rubber flush valve bulb having an aperture through its bottom and an elongated tapered flanged rubber guide passing thru said aperture and

depending form said bulb, being held thereto by the contact of its flange with the inner face of said bulb.

5. In combination, a hollow flush valve rubber bulb having an aperture thru its bottom and an elongated tapered flanged rubber guide passing thru said aperture and depending from said bulb, being held thereto by the contact of its flange with the inner face of said bulb, said guide having a longitudinal aperture therethru.

6. The combination of a tank, a discharge tube leading from said tank, a plate positioned transversely in said tube and having a transverse aperture, a valve seat, a valve, a detachable elongated tapered guide depending from said valve and positioned to pass reciprocally through the aperture of said plate.

7. The combination of a tank, a discharge tube leading from said tank, a plate positioned transversely in said tube and having a transverse aperture, a valve seat, a hollow rubber valve, a detachable elongated tapered hollow rubber guide depending from said valve and positioned to pass reciprocally through the aperture of said plate.

In testimony whereof I have signed my name to this specification.

HUBERT R. CRANE.
